US00D998019S

(12) **United States Design Patent** (10) Patent No.: **US D998,019 S**
 (45) Date of Patent: ** Sep. 5, 2023

(54) **LAMP FOR PHOTOGRAPHY OR CINEMATOGRAPHY**

(71) Applicant: **Aptolux, SIA**, Talsi (LV)

(72) Inventor: **Alvis Rozenbergs**, Talsi (LV)

(73) Assignee: **APTOLUX, SIA**, Talsi (LV)

(**) Term: **15 Years**

(21) Appl. No.: **29/792,665**

(22) Filed: **Apr. 14, 2022**

Related U.S. Application Data

(62) Division of application No. 35/510,755, filed on Oct. 30, 2020 (U.S. filing date under 35 U.S.C. 384), and having an international filing date of Oct. 30, 2020, now Pat. No. Des. 961,134.
